UNITED STATES PATENT OFFICE

141,922

DESIGN FOR A QUICK-WAY CABLE TAKE-UP

John C. Jaques, Denison, Tex.

Application April 9, 1945, Serial No. 118,919

Term of patent 14 years

(CL. D17—5)

To all whom it may concern:

Be it known that I, John C. Jaques, a citizen of the United States of America, residing at Denison, in the county of Grayson and State of Texas, have invented a new, original, and ornamental Design for a Quick-Way Cable Take-Up, of which the following is a specification, reference being had to the accompanying drawing, forming part thereof.

Fig. 1 is a perspective view of a quick-way cable take-up showing my new design, and

Fig. 2 is a plan view of the same on a smaller scale and showing a fragment of a cable therein for illustrative purposes only.

I claim:

The ornamental design for a quick-way cable take-up, as shown and described.

JOHN C. JAQUES.
